METHOD AND MEANS FOR MAKING A COVERING FOR SURFACES EXPOSED TO THE WEATHER

Winfred H. Outman, Richmond, Calif., assignor to Certain-Teed Products Corporation, New York, N. Y., a corporation of Maryland

Application May 29, 1931, Serial No. 540,846
Renewed May 14, 1937

23 Claims. (CL. 91-30)

This invention relates to the process of making a covering material for surfaces exposed to the weather, and more particularly to units in the form of strips made from sheet roofing having on the exposed surface thereof sections separated by space simulating stripes to simulate shingles or other structural units.

Shingle simulating units cut from sheets of suitable fibrous material or other fabric and impregnated with a waterproofing or weather resisting material have heretofore been known in various forms. In the manufacture of roofing, whether in the form of sheets or of units such as shingles or shingle strips, the surface of the impregnated felt commonly known as "roofing" ordinarily is covered with a coating of asphalt either on one side of the impregnated sheet or on both sides. This coating imparts not only an additional weather resisting quality to the roofing but also aids in providing resistance to wear and helps to give the felt the desired degree of stiffness and weight and to add to the mechanical strength.

To the surface of the asphalt coating a layer of surfacing material, usually of mineral or similar stable material in granular form, is applied to provide additional resistance to wear and to prevent the asphalt coating from "running" under the action of heat, thereby maintaining the coating of the asphalt upon the sheet and the protection of the felt against the weather.

One method of producing such sheets or units, especially of producing units in the form of strips in which the surface to be exposed is divided into sections simulating shingles or other structural units separated by a space simulating stripe or groove in the asphalt, is shown in the Letters Patent to Outman, No. 1,426,497. This patent discloses the method of making shingle strips by scraping channels or grooves in the adhesive asphalt coating on a moving sheet of roofing material, depositing granular material on the adhesive material and in the channels, embedding the granular material in the asphalt coating in the surfaces between the channels and then removing the granular material deposited in the channels. The granular material in suitable quantity and of suitable grain size and color to provide the desired surfacing effect heretofore has been applied over the width of the sheet without regard to the presence of the grooves or their ultimate purpose in simulating the spaces which require a character of surface different from that of the sections which they separate. It has, therefore, been the practice heretofore in carrying out the manufacture of covering materials ac-

cording to the prior process of Outman, following the embedding of the granular surfacing material in the portions or sections of the sheet representing the shingles or other units, to brush out the grooves by a suitable brush corresponding in width to the width of the groove and intended to be aligned therewith at a point in the travel of the sheet following its delivery from the place at which the granules are embedded in the sections. The material in the groove does not adhere as strongly to the asphalt at the bottom of the groove as to the fully coated sections partly because the amount of asphalt remaining in the groove is reduced in the process of scraping as heretofore practiced to a point where insufficient coating remains properly to bond the individual grains or granules thereto and partly because the granules lying in the bottom of the groove are not forced into the asphalt coating of the grooves so deeply as those adhering to the fully coated sections when the sheet is run over the pressure rolls referred to above. Nevertheless, some of the material adheres to the bottom of the groove and if it were left there would mar the intended effect of the groove or channel as a space simulating stripe or line of demarcation. This granular material clinging to the bottom of the grooves, therefore, is brushed out as just mentioned and this step in the process as heretofore practiced has been necessary.

In the use of the process just described certain other features have been found to be disadvantageous both in the carrying out of the process itself and in the product resulting therefrom which it is the object of the present invention to overcome. One of these disadvantages is that the material which is scraped from the grooves amounts to a considerable part of the total quantity of granular material applied to the sheet. As this brushed out material has a certain amount of asphalt adhering thereto, it is not suitable, without additional treatment, for re-use in such coating operations. Even when so treated an additional expense is involved and its value as coating material is reduced. It therefore is largely wasted, thus increasing the cost of manufacture.

A further objection to the process as heretofore practiced is that, owing to more or less unavoidable variations in the delivery of the sheet to the machine and of the control of this delivery, a somewhat uneven alignment in the running of the sheet results and difficulty is therefore experienced in maintaining the alignment of the grooves with the brushes for removing the granules from the grooves. It will be clear from a study of

the Outman process that of necessity the removal of the granular material and therefore the position of the brushes is remote from the point at which the grooves are formed and that as a result it is difficult or impossible suitably to associate and relate the action of the brush with the formation of the groove. Consequently the brush may act not only so that it does not properly remove the granular material from the groove as intended but also, by its imperfect alignment with the groove or the imperfect alignment of the sheet with the brush, it may remove some of the granular material embedded in the asphalt coating of the sections or shingle simulating areas. Thus is produced an imperfection in the product, the edge of the section or areas which ultimately simulate shingles or other units becoming uneven and irregular and taking on in the uncovered portions the character of the surface of the groove rather than of the surface of the unit simulated. When such imperfect strips or units are placed in a roof or other assemblage of units having sections divided by grooves, these imperfections become marked and spoil the desired effect.

Another difficulty experienced in the manufacturer of strips or other units made with the grooves or channels according to the prior Outman process is that of suitably controlling the amount of the coating removed by the scraping action in the formation of the groove in the asphalt coating so that enough of the coating will remain at the bottom of the groove to afford protection of the roofing felt but not sufficient to cause the granular material to become embedded therein. Not only has it been necessary to adjust as accurately as possible the setting of the scrapers or "irons" used to form the grooves, but it has been necessary to carefully shape the portion of the iron making the groove so as to produce the desired displacement of the asphalt coating without making a ragged edge on the shingle simulating section and preventing as far as possible uneven bulging of the asphalt adjacent to the groove in the areas to be used as shingle sections.

Other difficulties have been experienced in carrying out the Outman process. For example, the brushes must be run at high speed in order properly to brush out the grooves. This causes rapid wear of the brushes and frequent renewals with considerable expense. Furthermore, they must be made removable for this purpose, while at the same time they must be designed so as to move transversely of the running of the sheet to permit them to follow the "weave" of the grooves.

It is, therefore, an object of the present invention to provide a method and means of preventing the adhesion to the coating in the channels formed in the adhesive coating upon a sheet of covering material of mineral surfacing material other than that intended to surface these channels.

A further object of the invention is to provide a method and means by which units divided into sections by grooves formed in a weather-resisting coating upon a surface may be made without mechanical removal from the grooves of the surfacing material applied to the whole surface.

Another object of the invention is to provide a process of producing units having sections divided by space simulating grooves in the weatherproof coating, which space simulating portions themselves will have a substantial weatherproof coating.

A further object of the invention is to provide a

process of producing a shingle simulating strip having shingle simulating sections separated by stripes in the form of grooves to simulate the spaces between the shingles, which sections are coated with granular material to provide a surface simulating the shingle, while the groove presents a surface also surfaced with mineral material but of a character distinct from the shingle simulating surfaces and serving to demarcate said sections.

A still further object of the invention is to carry out the process of grooving an asphalt coated sheet of roofing material and of applying thereto granular materials of such degree of fineness or coarseness in the grooves and on the areas adjacent thereto respectively and in such relation to the operation of grooving that the areas separated by the grooves will simulate shingles or other structural units and the grooves will represent the spaces between the units.

The present invention, therefore, provides a process and an apparatus to produce a covering material having an adhesive coating thereon in which channels are formed to demarcate areas upon the surface of the covering into sections simulating structural units. In these channels a suitable material is deposited to form a surfacing upon the adhesive in the channel having a character to prevent the further adhesion thereto of any of the granular surfacing material spread upon the areas adjacent to the channel to provide a wear resisting surface of desired texture, color, or other characteristics as described above.

The material deposited in the channels is preferably a stable mineral product in granular form but of such grain size as not to fill the channel or groove or materially reduce the depth thereof. It, therefore, while effective to prevent adhesion to the adhesive coating of the groove of the granular surfacing material applied to the sheet for the purpose of producing the surfacing effects above mentioned, may help to preserve the space simulating characteristic of the groove. The character of the fine granular material deposited in the grooves may also be such that the texture and surface appearance of the groove is not only in contrast to the surface appearance of the areas adjacent the grooves but has an outstanding character of its own. It therefore itself may serve properly to present or accentuate the simulation of the space between shingles or of joints between structural units, such as masonry joints, or of other spaces or separating areas.

The product made according to the invention, therefore, may take many different forms, such as shingle strips having thereon the simulation of a plurality of shingles in which the channels or grooves represent the spaces between shingles, which shingles are represented by the surfaces covered with granular material separated by the channels, or such as covering units in strip form in which the groove may represent, for example, the horizontal joint of brickwork or in which the groove may be so formed in the strip or unit as to demarcate and accentuate the lower edge of a unit, simulating a clapboard of wood. All such products in which a channel is used, as has been described, may be produced according to the process hereafter described and are included within the scope of the invention. The product which is produced by my invention, therefore, may be broadly described as a covering material having an adhesive coating thereon in which channels are formed and having in the channels applied to the coating therein a material to prevent ad-

hesion of the granular mineral materials used for surfacing the covering.

The process of my invention comprises the formation of the channel or groove in the adhesive coating in any desired manner but preferably by the method described in the prior patent to Outman. The particular feature of my process consists in the deposition under suitable conditions of a suitable material in the channel or groove subsequent to the formation of this channel, preferably immediately following its formation, and in such a way that at least the bottom surface of the channel is suitably covered with said material which adheres to the adhesive coating left in the bottom of the channel but is not spread over the area of the surfaces adjacent to and separated from each other by the groove or channel.

In the application of my process I therefore form the groove in the adhesive coating as described and then apply the fine granular material to the surface of the groove and before spreading upon the sheet of covering material the granular surfacing material to produce the desired surface effect. Similarly to the prior process of Outman, I may spread this granular surfacing material without regard to covering the channels or grooves. In contrast to the method described in the patent to Outman, however, in my process it is unnecessary to provide means for removing from the channels or grooves the portions of the granular surfacing material which, according to the Outman process, unpreventably are deposited and adhere in the grooves. The material which falls into the grooves in the process of the present invention is prevented from adhering to the asphalt coating in the grooves and, therefore, for example, by merely suitably traversing the sheet so that the surface upon which the granular material is applied, i. e., the upper surface of the sheet, is caused at some point in the delivery of the sheet to be reversed, that is, to become the lower side of the sheet, the material resting in the channels or grooves will fall therefrom. As will be seen in the drawings and understood from the further description in connection therewith, if desired, this material may fall again into the hopper or supply from which it is delivered to the sheet.

It is further to be noted that, by properly relating the size of and the amount of the fine material applied to the grooves or channels to the depth of the groove and taking into consideration the size of the granular surfacing material, the step of embedding the granular surfacing material upon the surface of the sheet to produce the surfacing effect may be carried out without forcing into the adhesive at the base of the grooves any of the latter material resting in the grooves. Thus, not only is the said granular material free to fall from the grooves in the manner just described but, owing to the substantially complete separation provided by the fine granular material in the groove, none or substantially none of the granular surfacing material will remain adhering to the bottom of the grooves as is the case in the process of Outman. The use of the fine granulated material, therefore, makes possible not only a saving of the surfacing material which without loss or deterioration may fall directly again to the hopper or source from which the surfacing material is applied to the sheet, whereas in the prior process of Outman this material is wasted in the operation of brushing out the grooves, but the operation of brushing out itself is saved with

an attendant saving in the apparatus used and in the expense of upkeep thereof for effecting this brushing operation. With this is coupled an increase in production and consequent reduction of cost due to the higher speed at which the sheet may be run when the brushing operation is eliminated.

Other features and advantages of my invention include the proper coverage of the asphalt coating in the grooves with mineral surfacing, thus protecting the asphalt coating against the weather and preventing deterioration of this coating and subsequent reduction of the impregnation of the felt; an increased resistance to fire with the protection of the mineral surfacing as the fine material may completely cover the surface of the groove; a cleaner and sharper groove affording better demarcation of the areas simulating structural units.

As has been mentioned above, one problem which is met in the use of the process of Outman is that of making the brushes "track" or align themselves with the groove from which it is desired to brush the surplus material because of the transverse variation in the delivery of the sheet. According to the present invention, however, not only may the fine granular material be applied to the grooves to prevent the adhesion of the granular surfacing material in the grooves but this application may be made close to the point at which the formation of the groove is carried out, there being no intermediate step necessary between that of grooving the coating and applying the fines. Therefore, there is not only less effect of the transverse run or "weaving" of the sheet but it becomes possible so to relate the application of the fine grain material to the formation of the grooves that, relative to each other, they are substantially fixed even though relative to the sheet transversely thereof they may move in the same sense, preferably simultaneously in the same direction, and thus compensate for any irregularity in the delivery of the sheet and so insure the proper alignment for delivery of the fine material into the groove and the avoidance of deposition of this material upon the adjacent surfaces which are to be covered with the granular surfacing material.

Moreover, it is a feature of the invention so to control the flow of the fine granular material to the groove that in consideration of its depth, and in consideration of its width and the rate of movement of the sheet that this fine material is spread over the surface of the groove to give the proper coverage for protection of the coating of the groove and to prevent adhesion in the groove of the granular surfacing material used for the sections, while avoiding an excess of the fine material which would fall from the groove with the granular surfacing material when the direction of the travel of the sheet, as above mentioned, is reversed above the supply of the granular surfacing material.

As the place of delivery of the "fines" is close to the place at which the groove is formed, to insure proper delivery of these "fines" to the groove the position transversely of the sheet of the point at which they flow to the groove may be fixed relative to the point transversely of the sheet at which the groove is formed by the scraper or iron, or these points may be set or adjusted in a predetermined relation. In certain cases the desired result may be accomplished simply by fastening both the scraper and the spouts for the fines to the frame of the machine. However, if desired,

mechanism may be provided to cause both the scraper and the spouts to move laterally in a predetermined relation in accordance with the movement of the sheet. The invention is not limited to the specific mechanism to provide for this lateral movement but includes the method and means of applying the "fines" in a fixed or in a predetermined relation to the grooves or in a predetermined relation to the transverse motion of the sheet of roofing being treated.

More detailed description of the operations of the process and of the apparatus for carrying out the process as well as of the product produced thereby will be understood from the description to follow taken in connection with the drawings. It will be understood that these drawings are diagrammatic and merely typical of the application of my process in the production of covering materials of the type to which the process is applied. The examples of covering units discussed in the description are also merely typical and the process and apparatus are in no sense limited to the specific examples described.

Fig. 9 is a sectional view taken on line 8—8 of Fig. 5 showing the pressure member or scraper supported in relation to the sheet and in relation to the spouts for delivery of the fine granular material.

50 To illustrate the invention I have shown a long sheet of roofing material A which may be made of felt, or any other suitable fibrous material. This sheet is supported, guided and fed by a number of 55 constantly rotating rolls, and it moves in the directions indicated by arrows.

Figure 1 shows the apparatus substantially as disclosed in the Patent to Outman No. 1,426,497 with the addition of the hopper 55 for feeding the fine granular material. The devices for applying the adhesive coating and for forming the grooves therein and their operation are as described in said prior patent. Likewise the application of the granular surfacing material is 65 made from the hopper 13 as in said prior patent. In practicing the process as disclosed in said prior patent, however, it has been found necessary to scrape the channels or grooves formed by the pressure member or scraper 5 so that the 70 adhesive coating remaining therein will be a minimum. This has been necessary because some of the granular surfacing material which is applied from the hopper 13 over the whole surface of the sheet and in the grooves 6 formed 75 in the coating thereon adheres to the coating in

the grooves and to the sides of the grooves to such a degree as to make difficult its removal by means of the brushes 20 mounted on the shaft 19.

Moreover, in practicing the prior process it 5 has been found that it is necessary to revolve the brushes 20 at high speed in order to effect a proper removal of the granular material and a cleaning out of the groove so as to produce the desired contrast of the groove with the surface 10 of the adjacent sections and thereby to demarcate these sections and simulate the space between the units. Owing to the "weave" of the sheet the channels in the asphalt coating, even though these channels have been formed at a constant 15 distance from the edge of the sheet and from each other, move laterally relative to the positions of the brushes as the sheet travels under the brushes, and this necessitates a sideways movement of the brushes on the shaft 19 if the 20 brushes are properly to "track" in the grooves. Owing to the irregularity of such sideways movement of the sheet, it has been found practicable to secure the sideways movement as produced only by the "tracking" itself of the brushes in 25 the grooves 6. Variations in the resistance to this sideways movement of the brushes and other causes prevent perfect "tracking" and the brushes may therefore climb upon the mineral surfaced areas of the sheet, thus damaging the surface 30 thereof and marring the evenness of demarcation of the groove. When such climbing occurs, imperfect removal of the granular material adhering to the groove also results.

The operation involving the use of the brushes, 35 therefore, interferes with rapid production and owing to the abrasive action of the granular material the brushes wear out rapidly and require frequent replacements. This is expensive and adds materially to the cost of producing the 40 covering material whether in the form of sheets or strips with sections thereon demarcated by the channels. Moreover it has been found in practice that the abrasive action of the brushes and more particularly, contrary to the conception in 45 said prior patent, the removal of the necessary amount of adhesive to prevent adhesion of the surfacing material may weaken the material of the sheet and may cause rapid deterioration of the material along the line of the channels.

Following the brushing operation the sheet 50 may be and usually is suitably cut to form shingle strips or units of desired size and shape. It is therefore essential that the proper formation of the groove as well as the proper coverage of 55 the surfaces with surfacing material be completed before the sheet is subjected to this operation.

In Fig. 5 is shown a modified form of apparatus for coating a sheet of roofing with asphalt and for surfacing a coated sheet with mineral surfacing material. In this figure is shown the adaptation of the present invention to a machine of this kind. The roofing sheet A is led over guiding rolls 30 and 31 into the receptacle or tank 1 in which it passes under a roll 32 submerged in the liquid asphalt contained in the tank. The sheet thus becomes coated on both sides and upon passing out of the fluid asphalt in the tank it travels between rollers 33 and 34. 60 These rollers act to remove and return to the tank 1 the excess asphalt carried by the sheet. In this manner a substantially uniform coating of asphalt is applied to the sheet to form a 65 weatherproofing and weather-resisting layer 70 75

and to provide an adhesive upon which the mineral surfacing material may be subsequently applied to the sheet.

Upon leaving the rollers 33 and 34 the coated sheet passes above a pair of rollers 36, spaced somewhat apart, and below the pressure member or scraper 38 mounted between the two rollers 36 and so as to bear upon the upper side of the sheet. The rollers 36 support the weight of the sheet and receive the pressure brought upon the sheet by the pressure member or scraper 38. The scraper 38 is so positioned that the scraping edge or edges 39, which may be in the form of notches or teeth formed or cut in protrusions from the surface of the member 38, press into and remove or displace a portion of the asphalt coating to form the groove in the manner which has been described above.

In order properly to locate the pressure member 38 and to produce the desired scraping action while affording a certain flexibility, the member 38 is suspended by rods 45 from a suitable support 46 upon which are fastened brackets 47 to which the rods are attached. The rod 45 may be in two separate parts connected by turn buckles 48 to provide the desired adjustment of the pressure member 38 relative to the moving sheet. The bracket 47 is so constructed, as with a ball joint, that the pressure member 38 may swing slightly in the direction of the motion of the sheet in order that the pressure applied to the sheet and the effect of the scraping of the protrusions, or teeth, 39 may be produced by the action of the weight of the pressure member 38 acting against the "drag" of the asphalt coated sheet. The sheet upon delivery from the rolls 36, having passed under the pressure member 38, will be grooved with a number of grooves corresponding with the number of protrusions 39 upon the pressure member 38.

In the particular embodiment illustrated, as shown in Fig. 7 and Fig. 9, the member 38 is provided with three protrusions having notches therein to form the teeth 39 as shown in detail in Fig. 8. At the left hand of Fig. 7 is shown the arm 40, which is of somewhat longer length than the protrusions 39 and, with the corresponding arm on the opposite end of the member 38, serves as a guide for the roofing sheet A. Thus the location of the grooves 6 relative to the edge of the sheet may be, therefore, more or less constantly determined.

In accordance with the present invention, as has been described, fine granular material is applied to the grooves formed by the pressure member 38. This material may be of various kinds, such as sand, talc, finely divided or flake mica, or similar stable material which will adhere to the adhesive coating and present a dry surface to the superimposed surfacing material. In practice it has been found advantageous to use a finely divided slate from which the dust has been separated. While the particles are minute, they preferably have a surface and size of appreciable degree, that is, they are not finely comminuted or powdered. This finely divided material, therefore, is preferably sufficiently "sharp" to have a surface to which the asphalt will adhere or of sufficient extent to separate the asphalt coating from the surfacing material showered upon it, that is, it will not be completely covered with asphalt. While the material is of relatively small size or thickness and therefore occupies no appreciable depth in the groove, it is effective to prevent adhesion to the asphalt of the mineral surfacing

material which is subsequently applied to the roofing sheet.

In Fig. 5 adjacent to the portion of the pressure member 38, a hopper 55 is mounted and contains the fine slate. A feed roll 56 is provided below the hopper to deliver to a funnel or a plurality of tunnels 57 a controlled amount of the fine slate. The funnels 57 are connected at their lower ends to spouts or pipes 58 which are engaged by brackets 59 adjustably fastened upon the pressure member 38 by means of bolts 60. The bolts 60 are inserted through slots in the brackets 59 so as to permit the lateral adjustment of the bracket 59 relative to the member 38 and to its protrusions 39. The pipe or spout 58 may be made flexible so that by adjustment of the bracket 59 the discharge end of the spout may be properly positioned relative to the protrusions 39 and to the grooves 6 formed thereby. This flexibility also permits a motion of the member 38 carrying the brackets 59 engaging the spouts 58 relative to the funnel 57 and the hopper 55. By suitable modification of the construction, relative motion between the spouts 58 and the protrusions 39 may be provided to vary the point of application of the fine slate or to compensate for variations in the position of the groove upon the sheet.

The fine slate is preferably delivered in a continuous stream through the spout 58 into the groove 6 as the sheet travels continuously from under the pressure member 38. By suitably controlling the feed from the hopper 55, the fine slate is spread over the surface of the groove without being spilled upon the adjacent asphalt coated areas B. The fine slate adheres to the asphalt in the groove, the rate of delivery of the fine material being such as to cover the surface of the groove with substantially no excess material. As the asphalt coating is not yet hardened as it leaves the scraper, the fine slate adheres thereto. A certain degree of drying of the coating is effected after passage from under the spouts and the sheet may then be delivered under the hopper 55 containing the mineral surfacing material which is to be caused to adhere to the asphalt coated areas B.

In practice this surfacing material is usually of granular slate, although other stable surfacing materials, usually of mineral origin, may be used. Within the scope of the invention is included any suitable surfacing material which will adhere to the asphalt coating but will not adhere to the fine material in the grooves. The hopper 55 is provided with a feed roll 56 for delivery of the shower or stream of the surfacing material upon the sheet. The shower is delivered to the sheet over the full width thereof, the granular slate falling into the grooves as well as upon the areas B. The sheet carrying the granular surfacing then passes around the rolls 61 and 68 in a manner similar to that described in connection with Fig. 1. The granular slate applied to the areas B becomes embedded therein upon passing around the roll 61 and any excess material, including that which has fallen into the grooves 6, upon leaving the roll 61 falls again into the hopper 55 or is delivered thereto upon the surface of the roll 61. Since it is possible to deliver the fine slate to the groove in controlled amount and so to spread the material over the surface of the groove and thus to provide no substantial excess of the granular slate, there is substantially no "off fall" of the fine slate with the granular surfacing material re-

turned to the hopper 65. Thus there is no dilution of the granular surfacing material by the fine slate and all the material returned to the hopper 65 may be used again without waste for surfacing the sheet. The sheet is then delivered over the roll 68 to a suitable winding roll or it may be delivered to an apparatus for cutting the sheet, for example, transversely, into strips to simulate a plurality of units such as shingles.

10 The sheet upon passing around the roll 68 will then be covered on the areas B with the granular surfacing material to simulate the surface of shingles or other structural units and these areas B will be separated by the grooves 6 in which 15 the fine slate adheres but to which the granular surfacing material does not adhere, being prevented from so doing by the fine slate in the grooves. As will be seen from Fig. 4, a relatively thin layer of the fine material adheres to the bottom 20 of the groove and the coarser grain surfacing material adheres to the thicker coating of the areas B and is embedded therein. The thickness of the asphalt coating at the bottom of the groove may be appreciably greater in the product produced by the method of the present invention, as 25 shown in Fig. 4, as compared with the product produced according to the prior patent to Outman as shown in Fig. 3, thus affording a better protection for the sheet of roofing felt A at the point 30 where the grooves are formed and making possible a sharper groove because it is not necessary to remove or displace so much of the asphalt to form the groove. The effect of demarcation is retained or improved due to the sharpness of the edges of 35 the grooves, and the depth of the groove is not appreciably diminished by the deposition therein of the fine slate. Thus an improved product is obtained as well as the advantages in manufacture discussed above, particularly the elimination 40 of the operation of brushing out the excess granular material as applied according to the process of the prior patent to Outman.

In Fig. 5 and Fig. 9 the member 38 is shown suspended by a ball joint which permits lateral 45 or transverse movement of the member 38 relative to the coating and surfacing machine as well as permitting the longitudinal movement described above. This arrangement permits movement of the member 38 in accordance with the 50 "weaving" or lateral movement of the sheet A as it travels through the machine. The positions of the protrusions 39 relative to the sheet, therefore, are substantially constant. As the sheet is guided by the arms 40, it may move laterally to 55 a considerable extent relative to the other portions of the machine, while a substantially constant relation or a substantial parallelism of the grooves 6 to the edge of the sheet A is maintained, because of the arrangement of the pressure member 38 so as to move laterally with the 60 movement of the sheet. As will be clear from a study of Figs. 5 and 6, the spouts 58 through which the fine slate is delivered to the grooves are also arranged to move laterally with the pressure member 38. The fine slate, therefore, will 65 be delivered constantly into grooves regardless of the motion of the sheet A transversely of the machine. In other words, the arrangement shown provides for a fixed or a predetermined relation 70 between the protrusions 39 forming the grooves and the spouts 58 which deliver the fine slate to the grooves. This predetermined relation may be maintained, therefore, regardless of the "weaving" of the sheet as it travels through the 75 machine.

In the arrangement just described, provision is made for insuring delivery of the fine slate to the groove and the covering of the surface of the groove by this fine material. The cooperation of the means of delivery of the slate with the means for forming the groove is not dependent upon the location of the feeding hopper 65 and the funnels 57 with their spouts 58 lengthwise of the machine relative to the pressure member or scraper 38. It is within the scope of the invention that suitable structure may be provided so that the point of application of the fine slate may be more or less remote from the point at which the grooves are formed provided the point of application of the fine slate is intermediate 10 between the scraping member 38 and the place of delivery of the shower of granular surfacing material. It is to be noted, however, that in contrast to the method and means disclosed in the prior patent to Outman, in the present invention 15 it is possible to locate the spouts 58, suitably connected to the hopper 65 for supplying the fine slate, at a point in close proximity to the scraper 38. In many cases, therefore, it may be unnecessary to provide for the coaction transversely 20 of the machine of the spouts 58 with the pressure member 38. This will be especially the case when the pressure member 38, although mounted, if desired, so as to swing in the direction of the motion of the sheet as mentioned above, is mounted without provision for lateral movement, the sheet being guided by the arms 40 in a substantially constant relation to the protrusions 39. In this case it may be said that the sheet A passes 25 a point at which the lateral movement of the 30 sheet is prevented or reduced to a minimum and the deposition of the fine material in the grooves is accomplished at or adjacent this point.

The invention may be applied to the apparatus shown in the prior patent to Outman by mounting the hopper 65, as shown in dotted outline in Fig. 1, above the sheet as it passes from the roll 4 toward the hopper 13. The grooves formed by the pressure members 5 may be coated with fine slate by suitably feeding this material from the 45 hopper 65. The brushes 20 mounted on the shaft 19 may then be eliminated.

While the invention has been particularly described in the forming of continuous grooves in the asphalt coating of a sheet of roofing material and is of especial advantage when such sheets are subdivided, as by cutting transversely of the grooves, into strips or units having sections on the surface thereof simulating structural units such as shingles or other units, it has 50 general application in the treatment of sheet material to which an adhesive coating is applied upon which a layer of surfacing material is caused to adhere when it is desired that the sheet will have portions to which the surfacing material 55 does not adhere. By the deposition of suitable fine grained material or finely subdivided material of the desired color, texture or other characteristic, the adhesion of the surfacing material applied over the extent of the surface of the sheet may be prevented in those areas to which the fine grained material has been applied. Especially when a reduction in the thickness of the coating of the adhesive material is 60 desirable for the purpose of demarcation of the 65 surfaced areas or for the purpose of bending the sheet along the line of such reduced thickness or for other purposes, the application of the fine grained material is of advantage. This fine material serves the double function of prevention of 70 75 80 85 90 95 98

adhesion of the granular surfacing material and of assisting in the definition and demarcation due to the contrast of the fine material with the granular surfacing material. Such variations in use and application are within the scope of the invention.

Having described my invention, I claim—

1. The process of treating a sheet of covering material having upon its surface a coating of adhesive material which comprises moving said sheet in the direction of one dimension of its surface, forming channels in said coating extending in the direction of the motion of the sheet, feeding granular material toward said channels, and so adjusting the rate of feed with respect to the rate of movement of the sheet and the width of the channels that the granular material substantially covers the surface of the channels without appreciable deposition upon the surface of the coating adjacent the channels or of excess of said material in the channels.

2. The process of treating a sheet of covering material having thereon a coating of adhesive material which comprises continuously forming channels in said coating, continuously feeding granular material toward said channels, so adjusting the point of application of the feed of the granular material in relation to the sheet that said granular material is continuously deposited in said channels, and so controlling the amount of granular material fed to each channel that said material is deposited substantially only in registration with said channels and so as to substantially cover the surface thereof.

3. The process of producing a mineral surfaced covering material which comprises coating a moving sheet of fabric with an adhesive material, forming in said coating a plurality of separated channels longitudinally of the sheet as it moves, feeding toward said sheet and delivering at separated points adjacent said channels granular mineral material, and maintaining said delivery at said separated points in registration with the respective channels substantially to cover the surface of the channels only.

4. The process of producing a sheet covering material having thereon a coating of adhesive material surfaced with mineral surfacing material, which comprises moving the coated sheet in relation to a forming device so as to form a channel in said coating, delivering against the sheet as it moves a stream of granular mineral material, so restricting the width of said stream and so aligning its delivery with the channel as to direct said stream into said channel and to confine said delivery substantially to the channel, and varying the point of delivery to maintain said alignment with the channel.

5. The process of producing a mineral surfaced covering material which comprises applying a coating of plastic adhesive to a continuous moving sheet, scraping a groove in said coating lengthwise of the sheet, and delivering a stream of granular mineral material against the sheet in a predetermined relation transversely of the sheet to the scraping of the groove, whereby variations in the position of the groove transversely of the sheet are compensated.

6. In a machine for the manufacture of sheet covering material having thereon an adhesive coating, means for scraping a groove in said coating, and means acting with said scraping means in a predetermined relation to insure the deposition of finely divided mineral material substantially only in said groove.

7. In a machine for the manufacture from a

sheet of roofing material having a coating of asphalt thereon of a covering material having a plurality of grooves scraped in the asphalt coating, the combination with the means for scraping the grooves of means cooperating with said scraping means and in a predetermined relation thereto relative to the position of said scraping means transversely of the sheet for insuring the deposition of finely divided mineral material in said grooves.

8. In a machine for the manufacture of sheet covering material having thereon an adhesive coating, means for forming a groove in said coating, and means for delivering a stream of finely divided mineral material to said groove, and means for so controlling said delivery as to insure the deposition in the groove of said mineral material and to provide a substantially uniform coverage of the surface of the groove without substantial excess.

9. In a machine for the manufacture of sheet covering material having thereon an adhesive coating, means for causing lengthwise travel of the sheet, means pressing upon the coating to form a channel therein as the sheet moves, means for delivering to the channel finely divided mineral material, means for varying transversely of the movement of the sheet the position of the channel forming means relative to the machine, and means for varying transversely of the movement of the sheet and concomitantly with the variation of the position of said channel forming means the position of the means for delivery of fine mineral material, so as to insure the delivery of said material to the channel.

10. In a machine for the manufacture of sheet covering material having thereon an adhesive coating, means for causing travel of the sheet, means for grooving the coating as the sheet travels, means for delivering fine mineral material to the groove, and means for preventing substantial lateral motion of the sheet relative to the grooving means and the delivery means.

11. The process of treating a sheet of covering material having thereon an adhesive coating which comprises continuously forming across the sheet a channel in said coating, continuously feeding finely divided material into said channel, controlling the feeding so as substantially completely to cover the coating in said channel but avoiding deposition upon the surface of the coating adjacent said channel, and subsequently depositing coarser material upon the sheet without regard to the channel, the adhesion of said coarser material to the coating in the channel being prevented by the finely divided material therein.

12. The process of treating a sheet of material having demarcated upon a face thereof a stripe of defined width which comprises feeding granular material toward said face of said sheet and adjacent said stripe, and so controlling said feed with respect to the width of said stripe and with respect to its position upon the sheet as to insure that said granular material is deposited on the sheet substantially only in registration with said stripe.

13. The process of treating a sheet of material having demarcated upon a face thereof a stripe of defined width which comprises delivering toward said face of said sheet and adjacent said stripe a stream of granular material of limited cross-section, and so controlling said delivery and the cross-section of the stream with respect to the width of said stripe and the position of the stream.

with respect to the position of the stripe upon the sheet as to insure that said granular material is deposited upon the sheet substantially only in registration with said stripe.

5 14. The process of treating a sheet of material which comprises continuously demarking across the face thereof a stripe of defined width, continuously feeding granular material toward said face of said sheet and adjacent said stripe, and so controlling said feed with respect to the width of said stripe and with respect to its position upon the sheet as to insure that said granular material is deposited substantially in registration with said stripe to cover substantially only the 10 area of said stripe upon the sheet.

15. In a machine for the manufacture of a sheet material having bound upon a face thereof by an adhesive coating a layer of surfacing material upon areas separated by a stripe demarked 20 upon the surface of the coating, means for moving said sheet in the direction of the length of the stripe, and means for feeding and delivering toward the stripe upon the sheet granular material capable of adhering to the coating upon 25 the area of the stripe, said means for feeding and delivering said granular material being constructed and arranged substantially to confine said delivery to the area of said stripe to prevent adhesion to said area of the sheet of the granular 30 surfacing material subsequently applied to the face of the sheet for adhesion to the coating.

16. An apparatus comprising means for continuously moving an elongated sheet of material lengthwise of the sheet, means for continuously 35 marking upon the surface of said sheet a stripe lengthwise thereof, means for delivering toward the surface of the sheet a stream of granular material, said means for delivering the granular material being so constructed and arranged as 40 to confine the delivery of said granular material to the area of the stripe when in registration therewith, and means for producing co-action of said means for delivering the granular material to the stripe with said means for producing the 45 stripe to maintain registration of said delivery with said stripe.

17. In a machine for producing sheet roofing, means for continuously moving the sheet lengthwise thereof, means for continuously coating a 50 face of the sheet with an adhesive coating, means for continuously forming a stripe on said coating lengthwise of the sheet, means for delivering toward said sheet granular material, said means for delivering said granular material being so 55 constructed and arranged as to confine the delivery of said granular material to the area of the stripe, means for producing co-action of said means for delivering the granular material to the stripe with said means for producing the stripe 60 to maintain registration of said delivery with said stripe, means for applying to the whole surface of the sheet a layer of granular surfacing material and causing said surfacing material to adhere to the areas of the coating separated by 65 said stripe, and means for removing from the area of the stripe the granular surfacing material prevented from adhering to the coating by the granular material applied to the area of the stripe.

70 18. In a machine for producing sheet roofing, means for continuously moving the sheet lengthwise thereof, means for continuously coating a 75 face of the sheet with an adhesive coating, means for continuously forming a channel in said coating lengthwise of the sheet, means for deliver-

ing toward said sheet granular material, said means for delivering said granular material being so constructed and arranged as to confine the delivery of said granular material to the area of the channel when in registration therewith, 5 means for producing co-action of said means for delivering the granular material to the channel with said means for producing the channel to maintain registration of said delivery with said channel, means for applying to the whole surface a layer of granular surfacing material and causing said surfacing material to adhere to the areas of the coating separated by said channel, and means for removing from the area of the channel the granular surfacing material prevented from adhering to the coating by the granular material applied to the area of the channel, 10 said means for forming the channel being so constructed and arranged as to be capable of movement transversely of the motion of the sheet, said means for delivering the granular material to the channel being so connected to said means for forming the channel as to move transversely of the sheet in accordance with the transverse movements of said means for forming the 15 channel to maintain alignment of said delivery of the granular material to the channel.

19. The process of treating a sheet of material having formed in a face thereof a channel which comprises feeding granular material toward said face of the sheet and adjacent said channel, and so controlling the feeding with respect to the proportions of said channel and with 20 respect to its position upon the sheet as to insure that said granular material is deposited substantially only in said channel.

20. The process of preparing a covering material which comprises continuously moving an elongated sheet of material in the direction of its length, continuously coating a face of said 40 sheet of material with an adhesive coating, continuously pressing the adhesive coating to form therein a channel extending lengthwise of the sheet and to leave in said channel a relatively thin coating of said adhesive, continuously feeding toward said face of the sheet and adjacent said channel a stream of granular material of such grain size as not to occupy a substantial part of the depth of the channel, controlling the feeding of said granular material in relation to 50 the proportions of the channel and in relation to its position upon the face of the sheet so that said granular material is deposited only in said channel in amount sufficient to cover the surface thereof but insufficient to occupy a substantial 55 part of the depth of the channel, and subsequently covering said face of the sheet with granular material of contrasting character and causing it to adhere to the portions of said adhesive separated by the channel, said granular material in the channel substantially preventing said contrasting granular material from adhering to the coating in the channel.

21. The process of treating a sheet of material having demarked upon a face thereof a stripe of defined width which comprises feeding granular material toward said face of said sheet and delivering it adjacent said stripe, moving said sheet with respect to the point of delivery of said granular material and in the direction of the length of said stripe, controlling the feeding of said granular material with respect to the width of the stripe, aligning the delivery of said granular material with said stripe and varying the 70 75 80 85 90 95 98 99 100

position of the point of delivery of said granular material to maintain alignment thereof with said stripe, whereby said granular material is deposited substantially only in registration with said stripe.

22. Apparatus comprising means for marking a stripe across a face of a sheet of material, means for delivering granular material toward said face of said sheet, means for varying transversely of the direction of the stripe the position of said marking means, and means for varying transversely of the direction of the stripe and concomitantly with the variation of the position of said marking means the position of said means for delivering the granular material toward the

sheet to cause said delivery to register with said stripe.

23. The process of treating a sheet of material having formed in a face thereof a depression with a sharply defined edge demarking said depression from an adjacent portion of the surface of the sheet which comprises feeding granular material toward said face of the sheet and adjacent said depression and so controlling the feeding with respect to said sharply defined edge and with respect to the position of the depression on said sheet as to insure that said granular material is deposited substantially only in said depression to cover the depressed surface thereof.

position of the point of delivery of said granular material to maintain alignment thereof with said stripe, whereby said granular material is deposited substantially only in registration with said stripe.

22. Apparatus comprising means for marking a stripe across a face of a sheet of material, means for delivering granular material toward said face of said sheet, means for varying transversely of the direction of the stripe the position of said marking means, and means for varying transversely of the direction of the stripe and concomitantly with the variation of the position of said marking means the position of said means for delivering the granular material toward the

sheet to cause said delivery to register with said stripe.

23. The process of treating a sheet of material having formed in a face thereof a depression with a sharply defined edge demarking said depression from an adjacent portion of the surface of the sheet which comprises feeding granular material toward said face of the sheet and adjacent said depression and so controlling the feeding with respect to said sharply defined edge and with respect to the position of the depression on said sheet as to insure that said granular material is deposited substantially only in said depression to cover the depressed surface thereof.
